UNITED STATES PATENT OFFICE.

EDWARD M. MARS AND THOMAS H. MARS, OF CHICAGO, ILLINOIS; SAID
EDWARD M. MARS ASSIGNOR TO SAID THOMAS H. MARS.

NON-REFILLABLE BOTTLE.

SPECIFICATION forming part of Letters Patent No. 733,062, dated July 7, 1903.

Application filed February 17, 1903. Serial No. 143,791. (No model.)

To all whom it may concern:

Be it known that we, EDWARD M. MARS and THOMAS H. MARS, of Chicago, in the county of Cook and State of Illinois, have invented 5 certain new and useful Improvements in Non-Refillable Bottles, of which the following is a specification.

This invention relates to improvements in non-refillable bottles; and it has for its object 10 to provide a simple inexpensive construction which will prevent the refilling of the bottle unless the stopper or sealing device thereof be first destroyed.

The invention consists in the matters here- 15 after described, and more particularly pointed out in the appended claims, and the same will be readily understood from the following description, reference being had to the accompanying drawings, forming a part thereof, 20 and in which—

Figure 1 is an axial sectional view of the upper end portion of the bottle equipped with our improved sealing device, the latter being shown in side elevation. Fig. 2 is an axial 25 sectional view of the sealing device or stopper; and Fig. 3, a detail of the locking-ring, whereby the stopper is permanently fastened within the neck of the bottle.

Referring to the drawings, 1 designates as 30 a whole a bottle which may be of any suitable construction so far as its general features are concerned so long as it be provided with a relatively long neck 2, having an internal annular shoulder or inwardly-projecting ribs 3. Within the neck is seated the stopper, (designated as a whole 4,) which is 35 constructed and arranged as follows: 5 designates an outer shell, preferably of frangible material, such as glass, which is construct- 40 ed to approximately fit the neck, is of generally cylindric form throughout its principal length, and has a closed upper end 6. At a points intermediate the height of the shell it is provided with an external annular rib or 45 shoulder 6^a, which is adapted to engage and rest upon the annular shoulder 3 of the bottle-neck and limit the insertion of the stopper therein. At or near its lower end the shell is provided with a second external annular 50 projection 7, which is of small enough diam- eter to pass by the rib 3 of the bottle-neck

and the upper surface of which is perpendicular to the side walls of the shell. Upon this lower projection is seated an expander (designated as a whole 8) comprising a spring- 55 metal band-ring 10, provided with a plurality of upwardly-projecting spring-fingers 11, which are curved outwardly to normally bear in yielding engagement with the interior of the bottle-neck. The length of the expander-fingers 11 is such that when the shell is seated within the bottle-neck the upper ends of 60 said fingers fit closely beneath and are adapted to engage the under side of the rib 3 of the neck, the latter being to this end so shaped as to afford an abrupt shoulder, which positively prevents the withdrawal of the shell from the bottle. Within the shell is seated an axially-disposed cylindric tube 12, which is desirably of 65 uniform size throughout its length and is open 70 at both ends, with the exception that the lower end is slightly contracted to form a valve-seat 13, with which is arranged to co-operate a ball-valve 14. The tube 12 is arranged to extend 75 through corks or filling-pieces 15 and 16, ar- 80 ranged at the lower end of the shell and at a point intermediate the length of the latter, re- 85 spectively, the tube being thereby held reli- 90 ably in position and with its upper end 17 abutting against the closed upper end of the outer shell. The upper end of the shell is 95 provided with one or more longitudinally-ex- 100 tends slots 18 and also near its opposite or lower end with one or more longitudinal slots 19. The slots 19 are of considerable length and do not extend quite to the lower end of the tube, as shown clearly in Fig. 2. Within the tube is arranged a stopper or cork 20, which is located at a point intermediate the length of the slots 19 and serves to completely partition the interior of the tube. A second ball-valve 21 is arranged in the upper end of the tube above the cork 20 to more effectually protect against picking or otherwise interfering with the passage to and from the bottle. These ball-valves may both desirably be made hollow of glass or other material of suitable weight to act as float-valves. The shell is provided at points some distance below its upper end, but above the annular rib 3 of the bottle-neck, with a plurality of discharge-openings 22.

The operation of the device constructed and arranged as described is as follows: The bottle having been filled and the parts of the stopper assembled in the relation described, 5 the stopper as a whole is passed downwardly within the neck of the bottle until the spring-fingers 11 of the expander pass below and spring out beneath the annular rib 3. It may be noted at this point that the expander-ring 10 8 is split at one point to enable it to be assembled upon the shell. When it is desired to withdraw the contents of the bottle, the bottle is inverted and the ball-valves assume the positions indicated in dotted lines in Fig. 15 2. The liquid is then free to enter the inner end of the tube 12, passes thence out through the slots 19 to the space 23, from the latter back through the upper ends of the slots 19 into the tube, and again out through the slots 20 18 to the space 24 in the upper end of the shell. The liquid then passes out through the discharge-openings 22 and so escapes from the bottle.

Upon attempting to refill the bottle this is 25 obviously impossible so long as the bottle is maintained upright. Should the bottle be inverted and immersed in liquid, the ball-valve 14 acts effectively as a check-valve, which prevents entrance of the liquid, for as 30 soon as the liquid starts through the slots 19 it lifts the ball into the valve-seat 13, thereby obstructing the passage into the bottle.

It is to be particularly noted that the construction is such that it is impossible to insert any kind of tool or device so as to hold or fasten the balls against acting, and this is especially true with reference to the main lower check-valve 14. It is sometimes attempted to surreptitiously fill bottles of this 40 general character by fastening the valve member with glue or other adhesive, which is poured in in a liquid state and allowed to harden. Obviously this method cannot be worked successfully with the present construction. It is the intention to make the shell 6 of frangible material and sufficiently frail so that any serious tampering with the device will result in breaking the shell. This 45 does not render the device impractical, for 50 the reason that the stopper is completely enclosed within the neck of the bottle and therefore protected from injury. If desired, a protective stopper of cork or the like may be arranged within the neck above the stopper 55 proper, as indicated in the drawings.

We claim—

1. In a non-refillable bottle, the combination of a bottle provided with a neck, a stopper to fit within said neck comprising a cylindric shell of frangible material with closed upper end, means for seating said shell within said neck, an axially-disposed tube extending within said shell and having a valve-seat at its lower end, a movable valve-body 60 adapted to occupy said valve-seat, a pair of partitioning-diaphragms fitted within said shell and surrounding said tube, said tube

provided with lateral openings near its ends, said shell having lateral openings near its upper end, and means whereby said stopper is 70 permanently secured within the neck of said bottle.

2. In a non-refillable bottle, the combination of a bottle provided with a neck, a stopper to fit within said neck comprising a cylindric shell of frangible material with closed upper end, an annular external rib upon said shell intermediate its height, a co-operating annular rib within the neck of said bottle, an axially-disposed tube extending within said shell and having a valve-seat at its lower end, a movable valve-body adapted to occupy said valve-seat, partitioning-diaphragms fitted within said shell and surrounding said tube, one intermediate its ends and the other adjacent its lower end, said tube having lateral openings near its ends, said shell having a plurality of lateral openings near its closed end, outwardly-projecting members associated with said shell and having engagement 80 with the annular rib within said neck, whereby said shell is permanently held within said neck.

3. In a non-refillable bottle, the combination of a bottle provided with a neck, a stopper to fit within said neck comprising a cylindric shell of frangible material with closed upper end, an axially-disposed tube extending within said shell and having a valve-seat at its lower end, a movable valve-body adapted to occupy said valve-seat, a partitioning-diaphragm within said tube, a pair of partitioning-diaphragms within said shell and surrounding said tube, one intermediate its ends and the other adjacent its lower end, said tube having lateral openings near its ends, said shell having a plurality of lateral openings adjacent its closed end, a second valve-body within said tube above the dividing-partition therein, and outwardly-projecting 105 spring-like members associated with said shell and engaging the under side of said annular rib within said neck, whereby said stopper is permanently held within said neck, substantially as shown and described.

4. In a non-refillable bottle, the combination of a bottle provided with a neck having an internal annular projection and a stopper arranged to fit within said neck comprising an outer generally cylindrical shell of frangible material having a closed upper end, an annular external rib located at a point intermediate its height, adapted to engage the internal projection of the bottle-neck and limit the insertion therein, a lower external annular projection, a spring-expander fitting upon said lower projection, an axially-extending tube arranged within said shell and provided with an upper and a lower slot, an upper and a lower stopper arranged within said shell, through which stoppers said tube extends and whereby it is supported, a stopper arranged within the tube and so located therein as to divide the lower slot thereof and ball-

valves arranged within said tube above and below the stopper therein, the upper end of the tube being arranged to abut the closed upper end of the outer shell and the lower end of the tube contracted to form an annular valve-seat, and one or more outlet-ports in said outer shell located between the inter-

mediate outer projection and the upper end thereof, substantially as described.
